[57]

ABSTRACT

A vehicle body is disclosed having a floor and a pair of upstanding support members spaced apart in the direction of travel of the vehicle. Bands of strapping material are extended longitudinally in the body and have their opposite ends secured to the upstanding support members at points spaced above the floor, so that intermediate portions of the bands rest on the floor and their end portions slope upwardly toward the support members. A unitized load is placed on the intermediate portions of the bands and is spaced from the support members by the sloping band end portions, whereby upon impact the load may ride up the strap members to absorb impact energy.

METHOD AND APPARATUS FOR HANDLING ARTICLES IN TRANSIT

This application is a continuation-in-part of U.S. patent application Ser. No. 579,712, filed Sept. 15, 1966, now abandoned.

BACKGROUND OF THE INVENTION

1. Field of the Invention

The present invention relates in general to apparatus for and method of handling articles in transit and more particularly has for its primary purpose the provision of apparatus for use in railway cars to eliminate damage to articles during transit. An object of the invention is the provision of apparatus that permits the use of the principle of a floating load.

2. Description of the Prior Art

The transportation industry has long been plagued with load damage caused by shocks transmitted to the load by the vehicle. Loads carried by railroad freight cars are especially susceptible to damage because of the severe shocks that occur when the car stops or starts, especially during yard switching. It is well known in the industry that maximum damage will occur if the load is fixed with respect to the vehicle so that the full shock of impact is transmitted directly to the load. Therefore, many different devices and procedures have been developed over the years to permit relative movement between the load and the vehicle when shocks occur.

One broad approach to solving this problem has been to mount the load on a separate carriage which is then mounted on the floor of the vehicle. The carriage is provided with wheels or rollers so that it is movable with respect to the floor of the vehicle. To control the amount of relative movement between the carriage and the vehicle, some form of shock absorbing means are provided. In its simplest form, the shock absorbing means can be a spring that not only absorbs shocks but also tends to return the carriage to its original position after the shock has dissipated. In other cases, oppositely inclined ramp tracks have been used to dampen the movement of the carriage with respect to the vehicle. The Trumper et al. U.S. Pat. No. 3,273,516 that issued Sept. 20, 1966 discloses a shock absorbing assembly for vehicles in which longitudinal shocks are transmitted between a shock receiving frame and a load carrying frame by longitudinal shock absorbing assemblies including roller means and brake means, and preferably return spring means producing a uniform return spring force. The approach taken by Trumper et al. to solve this problem, and similar approaches taken by others before him, has not proven to be commercially acceptable. Constructing or modifying a vehicle in this manner is simply too expensive and complicated to permit any wide application of the concept.

Another approach to reducing load damage is the "shifting load" or "floating load" method of transporting merchandise. In this approach, a unitary load is permitted to shift freely on the floor of the vehicle except for the retarding effect of inertia and friction between the vehicle floor and the load. This method has proven to be highly effective in reducing load damage so long as sufficient space in the vehicle is provided over which the shifting can occur. With this approach, the shifting is cumulative because no means are provided to return the load to its original position. Because of this problem, the load in a boxcar, over a long trip, will often shift until it comes to rest against the end wall of the boxcar. At that point, no further shifting is possible and all shocks are transmitted directly to the load. Various attempts have been made to reduce the amount of shifting that occurs with a floating load, as for example by using braking devices between the load and the floor. One approach to braking or controlling this movement is shown in the Scales U.S. Pat. No. 1,920,917 that is issued Aug. 1, 1933. It is still true, however, with all variations of the floating load, that the movements are cumulative. If sufficient space is not provided, the load will eventually come to rest in a fixed position with respect to the vehicle so that all shocks are transmitted directly to it.

SUMMARY OF THE INVENTION

The present invention uses as its starting point the sliding or floating load method. Two or more bands of strapping material are extended along the floor of the vehicle in the direction of expected impact. The unitized load is placed on intermediate portions of the bands. The opposite ends of the bands are secured to the end walls of the car or to other upstanding support members in a plane above the plane of the floor. The end portions of the bands thus slope upwardly from the floor toward the point of connection to the end wall. The load thus rests directly on the floor with the strapping material being positioned between the floor and the load. Upon impact, the load is permitted to move with respect to the floor as is normal in a floating load situation. Therefore, a portion of the energy of impact is dissipated by inertia and friction between the floating load and the floor of the car. Very soon after impact, however, the load begins to slide upwardly on the sloping band end portions. The remaining energy of impact is stored in the load by sliding upwardly on the sloping bands. This remaining energy, which was exerted in a horizontal plane, is converted to stored energy in the load, which energy tends to act in a vertically downward direction to aid in restoring the load to its original position. This energy stored in the load therefore provides a restoring force that, once the impact energy is dissipated, forces the load to slide back down the sloping band portions until the stored energy is dissipated by frictional engagement with the floor. Because of the arrangement of the bands or straps, the angle between the load and the strapping passes through the entire spectrum from the angle before the impact to 90°. With this invention, the load will never come in contact with the end walls and, the shifting of the load is not cumulative. Therefore, larger loads can be placed on a given length of floor and no concern need be given to the length of the trip or the type of terrain through which the vehicle is traveling. Applicant's apparatus and method can be applied to almost any vehicle that can utilize the floating load method. The needed equipment is easy to install and the car in which the apparatus is installed can be quickly restored to normal use by merely removing the bands or straps. The present invention thus provides a simple and very effective means of reducing shock damage to loads during transit.

BRIEF DESCRIPTION OF THE DRAWINGS

- 45 FIG. 1 is a side view in section of a railway car showing the invention applied thereto;
 FIG. 2 is a view similar to FIG. 1 in which the load is in two parts;
 FIG. 3 is an enlarged side view of one means of securing strappings to the freight car end walls;
 FIG. 4 is another side view of a railway car, portions thereof being broken away, showing the invention applied thereto;
 FIG. 5 is an enlarged sectional view taken along line 5—5 of FIG. 4, showing the end wall of the railway car including a plurality of U-shaped strap securing means mounted therein;
 FIG. 6 is an enlarged fragmentary view in horizontal section taken along line 6—6 of FIG. 5, showing in more detail a pair of the generally U-shaped securing means mounted in the end wall;
 FIG. 7 is a greatly enlarged side view in vertical, longitudinal section of one end portion of the railroad car of FIG. 4, portions thereof being broken away, showing the normal position of the load in full lines and a position assumed by the load after impact in phantom;
 FIG. 8 is a side view of a railroad flat car, showing the invention applied thereto;
 FIG. 9 is a vertical sectional view taken along line 9—9 of FIG. 8, greatly enlarged, showing an upstanding support member and means for securing the bands passing thereover;
 FIG. 10 is a view in top plan of the structure shown in FIG. 9;
 FIG. 11 is an end view of a support member of the type shown in FIG. 8 in the folded position, the upstanding position thereof being shown in phantom, portions thereof being broken away and shown in section; and

FIG. 12 is a view in top plan of the railroad flat car of FIG. 8, with the load and bands removed, and with a plurality of support members lying in the folded position.

DESCRIPTION OF THE PREFERRED EMBODIMENTS

FIGS. 1-3

The novel features of the invention will appear more fully hereinafter from the following detail description when taken in conjunction with the accompanying drawings. It is expressly understood that the drawings are employed for the purpose of illustration only and are not designed as a definition of the limits of the invention, reference being had for this purpose to the appended claims.

In loading freight cars according to this invention the article or articles are not secured directly to the car and are permitted to float back and forth on the car floor, thereby dissipated the energy released when the car receives an impact. The impacts occur generally when the car is being coupled into a string of freight cars or when the car is hit by a string of freight cars.

It is important when employing the floating load principle to get the load to absorb, on impact, the energy of the impact without touching an end wall of the car and thereafter to return substantially to its original position.

Referring to the drawings, detail 10 indicates a railway boxcar but it is to be understood that the invention can be used with other types of cars, for example flat car with bulkheads, gondola, etc. The freight car consists of suitable running gear 12 and provided with floor 14, end walls 16, and coupling members 18.

Secured to the end walls of the car 10 are securing means for strap members of banding-like material. The securing means may be of any suitable type. The securing means may be "U" bolt type 28 arrangement. Steel banding or equivalent material is employed. The banding extends the length of the car, passing under the load and secured to the end walls of the car. The banding material is secured to the end walls a predetermined distance above the floor, by way of example 18 inches. Two or more steel bands are employed in this manner. The banding 22 varies in size depending on the weight of the load 20. If "U" shaped bolts are used in connection with banding 22 they are arranged parallel to the floor 14. When the load 20 tries to move in either direction, the load rides up on the bands 22 thus changing the horizontal movement to a vertical movement. This movement dissipates the energy of the impact.

Guide banding or straps 30 are used to keep the load 20 from moving to the side walls of the car 10. If U-shaped bolts are used they are arranged in a vertical plane with reference to the car floor 14. The guide banding 30 is preferably secured to the end walls above the point where banding 22 is secured to the wall 16.

In the end of the car 10 may be removably secured band securing devices 24 with a band receiving opening 26.

When the load is divided as shown in FIG. 2, a band support member 38 is removably secured to the car floor 14, the support being provided with top member 40 which has the edges 42 turned downwardly as above. In the divided load the banding straps 22 are secured to the end walls 16, pass under the load 32 over the band support 38, under the load 34 and are secured to the other end wall. The band support 38 is located in the space 36 between the unitized loads 32 and 34.

The articles to be shipped may be palletized or packaged in a normal manner. The securing means are placed in the railway car, the steel banding 22 being secured to the securing means at one end, laid on the floor 14 and extending the length of the car. The load is then put in the car 10, resting on the steel banding 22, the other end of the banding is then secured to the securing means. The guide bandings 30 are secured to the U-shaped bolts 28 or other securing means employed.

FIGS. 4-12

FIG. 4 discloses another railway boxcar 50 having suitable running gear 51, a floor 52 and a pair of opposite end walls 53.

A unitized "floating load" 55 is carried within car 50 directly on floor 52.

Each of the end walls 53 is provided with two, horizontally extending, spaced rows of generally U-shaped securing devices 57. The end wall 53 normally comprises a plurality of vertically extending wooden planks 53a to the outside of which is attached a corrugated metal sheet 53b. A suitable recess 58 is provided in the plank wall 53a for each of the securing devices 57. A horizontally extending metal or wood support bar 59 is positioned in one of the corrugations in the metal panel 53b. Preferably, support bar 59 extends the full width of the car and is provided with a plurality of openings or holes through which the arms of the U-shaped securing devices 57 extend. As best shown in FIGS. 6 and 7, nuts are threadedly secured to the ends of the arms to hold the securing devices 57 in position.

At least two bands 60 of strapping material extend between the ends 53 of the car with intermediate portions thereof positioned between load 55 and floor 52. Each end of each band 60 is formed into a loop 60a by folding the end of the band back against the band itself and securing the loop with a suitable clamping device 61. In this embodiment, before the loop 60a is formed, the end of the band 60 is inserted through one of the securing devices 57, and then is folded back and clamped as shown in FIGS. 6 and 7. The end portions of each band 60 thus slope upwardly from the plane of the floor at the end of the load toward a point on the end wall 53 located above the plane of the floor. As the weight of the load 55 increases, a larger number of bands 60 can be used to support the increased weight.

As shown in FIG. 5, it is preferable to provide more than one row of securing devices 57 so that the band 60 can be made to slope at a different angle if that appears to be desirable. It appears that the most effective angle between the band and the floor or between the band and the load is approximately 45°. This angle can be adjusted if more than one row of securing devices 57 are provided. The normal position of load 55 is shown in full lines in FIG. 7. Upon impact of the vehicle, the load will move up the sloping band portion to a position such as that shown in phantom. After the impact shock dissipates, load 55 will slide back down the bands 60 to nearly its normal full line position. This type of activity will repeatedly occur during a normal trip to thereby minimize shock damage to the load.

FIG. 8 discloses a railway flat car modified in accordance with my invention. The flat car has a floor 65 and suitable running gear 66. A unitized load 67 is supported on floor 65 between the ends of the car. As shown in FIG. 12, the floor 65 is provided with a plurality of pivotable support members 68 located at spaced intervals between the ends thereof. Each support member 68 is a rectangular wooden or metal member that extends to almost the full width of the car. As shown in FIG. 11, a recess or well 69 is provided in the floor 65 for each support member 68. A suitable hinge 70 is provided between one edge of support member 68 and floor 65 so that support member 68 can be swung into a folded position within recess 69 or into an upstanding position for use in supporting the bands of strapping material. Support member 68 can be locked in the upstanding position by a suitable folding arm member 71. If all of the support members 68 are folded down into their associated recesses 69, a flat, relatively smooth floor 65 is provided. This floor can be used in the normal manner.

In order to practice my invention, a pair of spaced support members 68 are locked in the upstanding position. A plurality of bands 60 of strap material are extended longitudinally along floor 65 with the ends thereof extending over the two spaced upstanding support members 68. A plurality of U-shaped securing devices 75 are provided, this time secured to the floor 65 within the recess 69. A row of these securing devices 75 are provided opposite the support member 68 from the load 67. After the bands 60 are extended along the floor 65, the load 67 is placed on an intermediate portion of each and the ends of each band are inserted through a corresponding

securing device 75, formed into a loop and clamped in that position. As shown on the drawings, the end portions of the bands 60 slope upwardly from the ends of the load, pass over the top of the upstanding support member 68 and are then secured to the securing devices 75. The upstanding support members 68 in this embodiment of my invention correspond to the end walls 53 of the previously described embodiment. In both cases, sloping band end portions are provided upon which the load can slide upon impact to dissipate the energy of impact.

Using the embodiment shown in FIGS. 8-12, loads of different lengths can be accommodated by using different pairs of support members 68. In addition, two or more loads can be accommodated on the same flat car in much the same manner as shown in FIG. 2.

My invention is applicable to any vehicle that will accommodate a normal sliding or floating load. The drawings of the present application show several different approaches to practicing my invention. The invention can also be used in semi-trailers, for example, especially where they are mounted on flat cars for transportation by train. In such cases, the semi-trailer is fixedly attached to the flat car. The present invention provides a means of loading the semi-trailer so that impact shocks are not directly transmitted to the load.

What is claimed is:

1. Impact shock reducing apparatus for a vehicle carrying a floating load on the vehicle floor between and spaced from a pair of support members, comprising:

- a. at least two spaced flexible strap members extending generally in the direction of expected shocks between said support members with intermediate portions thereof resting on the floor, said intermediate portions being positioned between the load and the floor; and
- b. means for supporting the end portions of said strap members on said support members at points spaced above the floor whereby upon impact the load may ride up the strap members to absorb impact energy.

2. The apparatus of claim 1 wherein said vehicle is a railroad car, and wherein said strap members are steel bands.

3. The apparatus of claim 1 wherein said support members are pivotally secured to the vehicle floor and wherein means are provided to hold said support members in an upstanding position and wherein open recesses are provided in said vehicle floor into which said support members are folded when not in use.

4. The apparatus of claim 1 wherein said strap members extend over said support members and wherein means are provided to secure the ends of said strap members to the floor opposite said support members from the load.

5. In a vehicle having a floor and a pair of upstanding support members spaced apart in the direction of travel of the vehicle and carrying a floating load on and frictionally engaged with the floor between and spaced from said support members, means for reducing shock to the load upon vehicle impact by permitting relative movement between the load and vehicle, and for preventing the load from contacting said sup-

port members upon initial or repeated impacts, comprising a plurality of spaced bands of flexible strapping material extending between said upstanding support members with intermediate portions thereof under said load, and means for securing the ends of said bands to said spaced support members at points spaced above the floor whereby upon impact of the vehicle the load may ride up the sloping band portions to absorb impact energy.

6. The apparatus of claim 5 wherein the load consists of at least two units which are spaced apart longitudinally on said intermediate band portions, together with an upstanding support positioned on said floor between the spaced apart load units, portions of said bands between the spaced apart units being elevated and passing over said support.

15 7. The combination of an elongated vehicle body having a floor and a pair of end walls, a unitized floating load on said floor between and out of contact with said end walls, securing devices secured to the end walls at points spaced above said floor, and at least two bands of flexible strapping material extending longitudinally in the vehicle body with intermediate portions of said bands extending beneath said load, the ends of said bands being secured to said securing devices so that the secured end portions of the bands slope upwardly from the floor toward the end walls, with the load being spaced away

20 25 from said end walls by said sloping portions of the bands, whereby upon impact of the vehicle body the load may ride up the sloping band portions to absorb impact energy without contact of the load with said end walls.

8. A method of loading a vehicle body having a floor and a

30 pair of support members spaced in the direction of travel of said vehicle, said method comprising the steps of extending at least two strap members between the support members with intermediate portions of said strap members resting on the floor, placing a load on said intermediate portions between and spaced from the support members, and supporting the ends of said strap members on the support members at points spaced above the floor so that end portions of said strap members slope upwardly from the floor toward the support members, whereby upon impact of the vehicle body the load may

35 40 45 ride up said sloping end portions to absorb impact energy without contacting the support members.

9. A method of loading a vehicle body having a floor, to reduce shock to the load upon vehicle impact, comprising the steps of mounting a pair of upstanding support members on

45 50 55 said vehicle body at spaced apart positions in line with the direction of expected impact, extending a plurality of elongated strapping means between said support members with intermediate portions thereof resting on the floor, placing a load on said intermediate portions between said spaced support

members, and securing the ends of said strapping means to said support members at points spaced above the floor so that end portions of said strapping means are taut and slope upwardly from the floor at the end of the load toward said support members, whereby upon impact of the vehicle body the load may ride up the sloping end portions to absorb impact energy.
